Assistant Examiner — Tia Ruth-Renee Polidori

(57) CLAIM

The ornamental design for a set of stackable coffee mugs with holder, as shown and described.

DESCRIPTION

The patent or application file contains at least one drawing executed in color. Copies of this patent or patent publication with color drawing(s) will be provided by the Office upon request and payment of the necessary fee.

1. Set of stackable coffee mugs with holder

1.1: Separated-Perspective

1.2: Assembled-Right

1.3: Assembled-Top

1.4: Assembled-Front

1.5: Assembled-Bottom

1.6: Assembled-Back

1.7: Assembled-Left

The portions of the set of stackable coffee mugs with holder shown in broken lines form no part of the claimed design.

1 Claim, 7 Drawing Sheets
